UNITED STATES PATENT OFFICE.

FRIEDERICH MÜLLER, OF HARTFORD, CONNECTICUT, ASSIGNOR TO PRATT & WHITNEY COMPANY, OF NEW YORK, N. Y., A CORPORATION OF NEW JERSEY.

MACHINE FOR MILLING KNUURLS.

1,287,732.

Specification of Letters Patent. Patented Dec. 17, 1918.

Application filed May 9, 1917. Serial No. 167,396.

To all whom it may concern:

Be it known that I, FRIEDERICH MÜLLER, a citizen of the United States, residing at Hartford, in the county of Hartford and State of Connecticut, have invented certain new and useful Improvements in Machines for Milling Knurls, of which the following is a specification.

The invention relates to a milling machine primarily intended and adapted for the cutting of spiral grooves in cylindrical blanks to form knurls. It will be understood, however, that while the machine is especially adapted for forming knurls, it may by suitable modifications, be adapted for other uses, and it will further be understood that several of the parts of the machine may be used separately from other parts and may be embodied in machines quite different in construction and operation.

One of the objects of the invention is to provide a knurl milling or equivalent machine having two or more spindles upon which knurl blanks may be carried to be simultaneously milled. Another object of the invention is to provide improved means whereby all of the spindles may be simultaneously and uniformly indexed. A further object of the invention is to provide improved means whereby the knurl blanks and the milling cutters are separated from each other on the return movement.

Another object of the invention is to provide improved means whereby right or left spiral grooves may be formed as required. Another object of the invention is to provide means for stopping the operation of the machine after a blank has been completely milled. Still another object of the invention is to provide an improved indexing mechanism. Additional objects of the invention will be apparent from the following specification and claims.

In the accompanying drawings I have shown the embodiment of the invention which I now deem preferable, but it will be understood that the invention can be embodied in other ways and that the drawings are intended to be merely illustrative and are not intended to define or limit the scope of the invention, the accompanying claims being relied upon for that purpose.

Of the drawings:

Figure 1 is a plan view, certain of the parts being shown in section along the line 1—1 of Fig. 2.

Fig. 2 is a front elevation. In this view the mechanism which supports the blanks to be milled is shown in an abnormal intermediate position for the sake of convenience of illustration.

Fig. 3 is a vertical sectional view taken along the line 3—3 of Fig. 2. In this view also the mechanism which carries the blanks to be milled is shown in abnormal intermediate position for the sake of convenience of illustration.

Fig. 4 is a fragmentary vertical sectional view taken along the line 4—4 of Fig. 3, the parts of the machine being shown in the same relative positions as in Figs. 2 and 3.

Fig. 5 is a diagrammatic view showing a development of the cam for moving the mandrel carrying carriage.

Fig. 6 is a perspective view showing the cam for turning the mandrel carrying spindles.

Fig. 7 is a fragmentary view showing the indexing mechanism in a position different from that shown in Fig. 2.

Fig. 8 is a fragmentary view showing the indexing mechanism adjusted for operation in the opposite direction.

Referring to the drawings, 1 is a base or bed upon which the other parts of the machine are mounted. Extending upward from the bed 1 is a housing 2 and mounted in suitable bearings in the housing are one or more cutter spindles. Preferably I provide three spindles 3, 4 and 5 as shown, but it will be understood that the number may be varied without departing from the spirit of the invention. In fact, so far as certain features of the invention are concerned, a single spindle may be provided. Each spindle is arranged horizontally, and when there is a plurality of spindles they are arranged in parallelism in the same vertical plane and are preferably equally spaced. Mounted on the spindles are milling cutters 6 of suitable form, and for milling knurls these are usually simply V-shaped cutters. The several cutters are arranged with their cutting points all in the same vertical plane.

Suitable means are provided for driving

all of the cutter spindles in unison, and as shown, all of the spindles are driven from a common drive shaft 7 provided with a belt wheel 7^a. The shaft 7 carries a gear wheel 8 which meshes with gear wheels 9 and 10 mounted respectively on the upper two spindles 3 and 4. There is also provided an idler gear 11 which meshes with the gear 10 on the intermediate spindle 4 and also with a similar gear 12 on the lower spindle 5. By means of this gearing all of the spindles are rotated continuously in the same direction.

Carried by the lower part of the base 1 is a frame 13 which carries the devices for holding and for moving and adjusting the blanks to be milled. Supported on the frame 13 is a carriage 14 which is horizontally movable along lines which are normally at an obtuse angle to the axes of the spindles 3, 4 and 5 as shown in Fig. 1. Longitudinally arranged on the carriage 14 are one or more horizontal work carrying spindles, the number of spindles being the same as the number of the cutter carrying spindles. These spindles are shown at 15, 16 and 17 and are positioned in the same vertical plane, being equally spaced. Each spindle is formed with a socket adapted to receive and impart rotative motion to a mandrel 18. The several mandrels 18 are of such size and shape as to be adapted to receive and hold the blanks to be milled. As shown, each mandrel is provided with a nut 19 for locking the blanks in place. In practice, when knurls are being milled, two blanks are mounted on one mandrel.

Preferably supplemental bearings are provided at the ends of the mandrels, these bearings being in the form of bushings 20 mounted in a bracket 21 which is supported on the frame 13 independently of the carriage 14. Preferably the bushings 20 are longitudinally adjustable so as to give the maximum amount of support to the mandrels under varying circumstances. As shown, there is provided a set screw 22 in connection with each bushing for locking it in adjusted position.

For moving the carriage 14 and the spindles and mandrels carried thereby with respect to the cutters 6, I provide a rotatable cam drum 23 which is engaged by a roller 24 depending from the carriage. The drum 23 is secured to a horizontal shaft 25 which is mounted in bearings in the frame 13. Formed in the periphery of the drum 23 is a cam groove in which the roller 24 is positioned. A development of the drum 23 is shown in Fig. 5.

For turning the shaft 25 and the cam drum thereon there is provided a worm wheel 26 which is secured to the shaft and which meshes with a worm 27 secured to a vertical shaft 28. The vertical shaft 28 car-

ries a bevel gear 29 which meshes with a bevel gear 30 on a horizontal shaft 31. This shaft 31 is mounted in bearings on the housing 2 and is driven from the main drive shaft 7 by means of a belt 32 passing over pulleys 33 and 34. It will be seen that by means of the mechanism described, power will be transmitted from the main drive shaft 7 to rotate the shaft 25 and the drum 23. As the drum rotates the roller 24 engaging the sides of the cam groove will cause the carriage 14 and the parts mounted thereon to slowly reciprocate. The groove is so formed that the movement of the carriage in the forward direction (that is toward the cutters) will be quite slow, whereas the return movement away from the cutters will be much faster. It will be understood that milling of the blanks is effected during the slow forward movement of the carriage and that no milling takes place during the more rapid backward movement.

Preferably as shown at 35 in Fig. 5, the cam drum 23 is provided with a supplemental groove which permits the carriage 14 to be moved backward to an abnormal extent when necessary. This supplemental groove 35 is so positioned that the roller 24 is in alignment with it when the carriage is in its rearmost normal position. When the parts are in this position the carriage can be moved still farther backward to entirely withdraw the mandrels 15 from the bushings 20 and to give ample space for the removal of the lock nuts 19 and the blanks carried by the mandrels. After the milled blanks have been removed and other blanks have been put in place, the carriage can be again moved forward into position for normal reciprocation. Preferably, in order to conveniently effect this abnormal backward movement of the carriage, there is provided a rack 36 on the carriage which is engaged by a pinion 37 on a short horizontal shaft which carries a hand wheel 38, and by turning the hand wheel the carriage can be moved backward and forward in the way described.

Means are provided for effecting relative movement vertically between the cutter carrying spindles 3, 4 and 5 and the work carrying spindles 15, 16 and 17. In this way the machine can be adjusted to accommodate blanks of different diameters or to vary the depths of the grooves which are cut. Preferably this adjustment is effected by moving the cutter carrying spindles, and in order that this may be done, the spindles instead of being mounted directly on the housing 2 are carried by a slide 39 which is vertically movable on the housing. This slide is under the control of a screw 40 and by means of this screw the slide may be raised or lowered as required. For locking the slide in adjusted position there is provided a beveled gib 41 which can be clamped be-

tween the slide and the housing by means of screws 42.

As already stated, milling is effected during each forward movement of the carriage, 5 and in order that the cutters may not mar or additionally cut the blanks during the return movement of the carriage, I provide means whereby the blanks and the cutters are separated during the return movement of 10 the carriage. Preferably the carriage is lowered, thus holding the blanks away from the cutters. As shown in the drawings, the carriage 14 is not carried directly by the frame 13 but on an intermediate apron plate 15 43 which at one side is pivotally connected to the frame 13 by means of pivot pins 44, 44. Interposed between the other side of the plate 43 and the bottom part of the frame 13 is a pair of toggle links 45 and 46. The 20 upper link is pivoted to the apron plate at 47, the bottom link is pivoted to the frame at 48 and the two links are pivoted together at 49. When the links are in alignment with each other, as shown in Fig. 2, the plate 43 is in its upper position and the blanks are held in position to be milled. When the toggle is broken as shown in Fig. 4 the plate 25 43 is swung downward about the axes of the pivot pins 44, 44 and the blanks are removed from operative relationship with the cutters. For moving the toggle links to effect the above described movement of the plate 43 and of the blanks, I provide a cam disk 50 secured to the shaft 25. This disk 30 is provided with a cam groove in which is positioned a roller 51 carried by the pivot pin which connects the two toggle links at 49. The cam groove in the disk 50 is so shaped and positioned with respect to the 35 cam drum 23 that the links 45 and 46 are held in alignment during the normal movement of the carriage and are then moved out of alignment to lower the blanks during the return movement of the carriage.

40 Preferably, in order to limit the upward movement of the plate 43 and to hold the plate absolutely rigid during cutting, I provide two vertical stop rods 52, 52 which are threaded into the bottom part of the frame 50 13 and which are provided with heads which are positioned in recesses in the plate 43. Preferably these recesses are covered by disks 53, 53.

45 As shown in Fig. 3 the pivot pin at 48 has bearings at both sides of the link 46. The central part of the pin which is engaged by the link is eccentric. It will be clear that by turning the pin the link may be raised or lowered, thus making it possible to so 55 adjust the toggle that it will press the plate 43 firmly up against the heads on the rods 52. The pin 48 may be turned by means of the squared end at 54 and may be locked in adjusted position by means of the set screw 55.

60 65 In order that spiral grooves may be cut in

the blanks, means are provided for turning the spindles 15, 16 and 17 as the carriage advances. To provide for the turning of all of the spindles simultaneously and to the same extent, they are connected together by 70 suitable gearing. As shown in Fig. 3, the spindles are provided respectively with gear wheels 56, 57 and 58. As shown by dotted lines in Fig. 4, the two gear wheels 56 and 57 mesh with an idler gear 59 and the two 75 gear wheels 57 and 58 mesh with an idler gear 60. In this way all three of the spindles are connected for simultaneous and uniform movement. For turning the spindles one of them (preferably the middle spindle 80 16) is mounted in a sleeve 61 which is provided with a spiral groove 62 (see Fig. 6). The angle of the groove 62 is the same as the angle which the grooves to be cut in the blank are to have. The body part of the 85 carriage 14 adjacent the sleeve 61 is provided with a longitudinal slot 63, and projecting upward from the plate 43 adjacent the slot 63 and the groove 62 is a bracket 64. This bracket carries a pin 65 which extends 90 into the slot 63 and which carries at its end a roller 66 positioned in the groove 62. It will be seen that as the carriage 14 is moved longitudinally carrying with it the sleeve 61, the roller 66, by virtue of its engagement with the sides of the groove 62, will cause the sleeve 61 to turn. The sleeve carries with it the spindle 16 which, through the gearing which has been described, turns the other spindles 15 and 17. The spindles 100 are turned in one direction when the carriage advances and in the opposite direction when the carriage is withdrawn.

In order that the carriage may be moved backward by the hand wheel 38 as already 105 described, a groove 67 is provided which joins the groove 62. This groove is parallel with the axis of the spindle and the result is that when the carriage is moved backward the spindles are held against turning.

110 A suitable indexing mechanism is provided for causing a series of evenly spaced grooves to be cut in the blanks, and preferably this indexing mechanism is constructed to work automatically. As shown in Figs. 115 1, 2, 3 and 6, two disks 68 and 69 are secured to the rear end of the spindle 16. The sleeve 61 is provided at its rear end with a flange 70 which lies closely adjacent the disk 68. The disk is provided with a series of 120 notches 71, there being as many notches as it is desired to have grooves in the finished blanks. As shown most clearly in Fig. 3, there is provided a plunger 72 which is mounted in a radial aperture in the flange 125 70. This plunger is normally pressed inward by means of a coil spring. Projecting from one side of the flange is a tooth 73 which is adapted to engage one or another of the notches 71 in the disk 68, thus locking 130

the disk and the flange together and in this way positively connecting the sleeve 61 with the spindles 16, 15 and 17.

The body part of the carriage is provided with a T-slot 74 which is in the form of a circular arc concentric with the spindle 16. Adjustably held in place by means of a bolt engaging the slot 74 is a block 75 on which is pivotally mounted a latch 76 having a cam projection 77. A spring normally holds the latch in the position shown in Fig. 2, but the latch can swing when necessary in the counter-clockwise direction against the pressure of the spring. The plunger 72 is provided with a pin 78 which is adapted to engage the cam projection 77 of the latch 76.

At the beginning of the forward movement of the carriage the pin 78 occupies a position at the left of the cam projection 77, assuming that right-hand grooves are to be cut. As the carriage moves forward the pin moves toward the right moving under the projection 77, the spring yielding to permit such movement. However, when the carriage is moved backward the pin 71 will be moved toward the left and will engage the cam projection 77 and will be forced up the inclined surface thereof. As the pin is forced upward it moves the plunger 72 outward and disengages the tooth 73 from its notch in the disk 68, thus momentarily disconnecting the disk from the flange 70.

Rotatably mounted for movement about the axis of the spindle 16 is an arm 79. This arm is bifurcated, the two parts thereof having bearings at opposite sides of the disk 69. Mounted in the arm 79 is a radially movable plunger pressed inward by a coil spring. The plunger is provided with a beveled tooth 80 adapted to engage ratchet teeth formed on the periphery of the disk 69. The spring is of sufficient strength to normally hold the tooth in engagement with the disk without relative movement.

Formed in the body part of the carriage at opposite sides of the center thereof, are two T-slots 81 and 82 each in the arc of a circle and concentric with the spindle 16. Held in place by means of a bolt engaging the T-slot 81, is a block 83. Slidably mounted in this block is a plunger 84 which is inclined as shown and which is normally pressed downward by means of a coil spring. Held in place by a bolt engaging the T-slot 82 is a block 85. Slidably mounted in this block is a plunger 86 which is inclined as shown and which is normally pressed downward by means of a coil spring. The two plungers 84 and 86 are similar to each other and are similarly mounted except that they are oppositely inclined. The block 83 is so adjusted that the plunger 84 is held in position to engage the arm 79 near the end of the forward movement of the carriage, that is, near the end of the clockwise move-

ment of the spindle 16 and the associated parts. This engagement of the arm 79 with the plunger 84 causes the tooth 80 to slip relatively backward over one or more teeth of the disk 69. Near the end of the subsequent backward movement of the carriage and the corresponding movement of the spindle 16 and the associated parts in the counter-clockwise direction, the arm 79 is carried into engagement with the plunger 86 which is properly adjusted in position. This engagement of the arm 79 with the plunger 86 prevents the continued movement of the disk 69 and of the disk 68 which is connected therewith. The parts are so adjusted relatively that this engagement of the arm 79 with the plunger 86 takes place at the instant when the tooth 73 is disengaged from the disk 68 in the manner already set forth. The result is that the flange 70, together with the tooth 73, continues to move while the disk is held stationary. This additional movement of the flange 68 and of the tooth is sufficient to bring the tooth opposite the next notch 71 of the disk, into which notch the tooth moves when disengaged by the cam projection 77. In this way the disk 68 and also the spindle 16 and the other spindles 15 and 17, are moved through an angle corresponding to the distance between two of the teeth 71, thus positioning the blanks for the cutting of another set of grooves therein. The operation which has been described takes place repeatedly, the blanks being turned repeatedly through the same small angle until a complete revolution has been made.

Ordinarily for milling knurls it is necessary to provide one or another of three standard pitches. I therefore provide three sets of disks 68 and 69, these being similar to each other except for the numbers of teeth.

Preferably means are provided for automatically stopping the machine after the spindles have been indexed through a complete revolution. The mechanism shown comprises an arm 87 which is frictionally held on the end of the spindle 16. This arm has a central longitudinal flange 88. There is also a lever 89 pivotally mounted at 90. The lever 89 carries a pin 91 which projects through an aperture in a block 92. Engaged by the end of the pin 91 is a ring 93 connected to the lower end of a chain 120 or cord 94. This chain or cord extends to a suitable device for interrupting the power. This device is not shown as it constitutes no part of the invention, but for convenience it may be assumed to be a weight or spring operated belt shifter. During normal operation of the machine the ring is engaged by the pin, as shown, and power is continuously applied to the belt wheel 7^a on the drive shaft 7. When the operation 130

of the machine is first started the arm 87 is positioned with the longitudinal flange 88 thereof immediately below the point of the lever 89. During indexing the arm 87 is 5 rotated intermittently with the disks 68 and 69, being at the same time reciprocated with the carriage 14. After indexing has taken place through a complete revolution, the flange 88 of the arm 87 is brought into horizontal alignment with the point of the lever 89 with the result that upon the next backward movement of the carriage the arm and the lever engage. The arm is swung, thus 10 withdrawing the pin 91 into the block 92 and disengaging it from the ring 93. The chain or cord 94 is now free to move upward, thus interrupting the transmission of power.

The operator now moves the carriage 20 backward still farther by means of the hand wheel 38 in the way already described. The milled knurls are then removed from the mandrels and new blanks put in place. Then the carriage is returned to normal 25 position and the machine is started by pulling downward on the cord or chain 94 and engaging the ring 93 with the pin 91.

For the milling of knurls it is necessary 30 to provide not only for the cutting of right-hand spiral grooves but also for the cutting of left-hand spiral grooves. In fact, knurls are usually supplied in pairs, one left-hand and one right-hand. A machine embodying my invention is adapted for forming 35 grooves of either sort. Up to the present point I have referred solely to the cutting of right-hand spiral grooves, and I will now describe the manner of cutting left-hand spiral grooves.

The frame 13 is not fixedly connected with 40 the base 1 but is movable thereon about a vertical axis which is coincident with the axis of the shaft 28, this shaft in fact serving as a pivot pin. Bolts 95, 95 are provided 45 for locking the frame 13 and the base 1 together, the base 1 being provided with two sets of holes, thus permitting the frame 14 to be locked either in the position shown in full lines in Fig. 1 or in the position indicated by dotted lines in Fig. 1. The full 50 line position is used for cutting right-hand spirals and the dotted line position for cutting left-hand spirals. It will be seen that inasmuch as the frame 13 is movable about the axis of the shaft 28, the power connection 55 with the shaft 31 is maintained notwithstanding the movement of the frame.

For cutting left-hand spirals it is necessary 60 to turn the spindles 15, 16 and 17 in the direction opposite to that before described. In order to provide for such opposite turning the sleeve 61 is preferably provided with a second groove 96 which is similar to the groove 62 except that it is 65 oppositely inclined. There is also a groove

97 which joins the groove 96 and is similar to the groove 67. By unscrewing the bolt 65 the roller 66 may be removed from the groove 62 and then the sleeve 61 may be turned to permit the roller to enter the 70 groove 96.

For indexing, the disk 69 and the arm 79 are removed from the spindle 16 and reversed as shown in Fig. 7. Held in place by a bolt engaging the aforesaid T-slot 74 75 is a block 98 carrying a spring-pressed latch 99 having a cam projection 100, these parts being similar respectively to the parts 75, 76 and 77 except that they are oppositely formed. In operation, the pin 78, at or near 80 the beginning of the forward movement of the carriage, moves counter-clockwise past the cam projection 100 causing the latch 99 to swing against the action of the spring. Near the end of the forward movement of 85 the carriage the arm 79 engages the plunger 86, thus causing the tooth 80 to slip over one or more teeth on the disk 69. Near the end of the backward movement of the carriage the arm 79 engages the plunger 84, 90 thus stopping the turning movement of the disks 68 and 69. At substantially the same time the pin 78 is forced upward along the inclined surface of the cam projection 100, thus disengaging the tooth 73 from its notch 95 in the disk 68. The flange 70 with the tooth 73 continues to move and when the pin 78 has passed the cam projection 100 it drops into the next notch of the disk 68, thus indexing the spindles through an angle 100 corresponding to the distance between two notches.

What I claim is:

1. The combination in a milling machine of a plurality of parallel blank-carrying 105 spindles, a plurality of rotatable milling cutters adapted respectively to engage blanks carried by the spindles and having their cutting planes coincident and at an angle to the plane of the spindle axes, and 110 means for relatively moving the spindles in unison longitudinally and for simultaneously turning them to effect the milling of spiral grooves in the blanks.

2. The combination in a milling machine 115 of a plurality of parallel blank-carrying spindles, a plurality of rotatable milling cutters adapted respectively to engage blanks carried by the spindles and having their cutting planes coincident and at an 120 angle to the plane of the spindle axes, means for relatively moving the spindles in unison longitudinally and for simultaneously turning them to effect the milling of spiral grooves in the blanks, and means for moving the cutters in unison toward or from the axes of the spindles to change the depth 125 of the grooves.

3. The combination in a milling machine 130 of a plurality of parallel blank-carrying

spindles, a plurality of milling cutters rotatable about parallel axes and adapted respectively to engage blanks carried by the spindles, means for relatively moving the 5 spindles in unison longitudinally, means for connecting the spindles together for simultaneous rotative movement, an element carried by one of the spindles and having a spiral cam groove, and a roller projecting into the 10 groove and fixed against longitudinal movement whereby the spindles are turned during longitudinal movement.

4. The combination in a milling machine of a plurality of parallel spindles, blank-holding mandrels carried respectively by the 15 spindles, a plurality of milling cutters rotatable about parallel axes and adapted respectively to engage blanks on the mandrels, means for longitudinally reciprocating the spindles and mandrels, and bearings 20 for supporting the ends of the mandrels, the said bearings being normally non-reciprocating but manually adjustable longitudinally.

25 5. The combination in a milling machine of a plurality of parallel spindles, blank-holding mandrels carried respectively by the spindles, a plurality of milling cutters rotatable about parallel axes and adapted respectively to engage blanks on the mandrels, means for longitudinally reciprocating the 30 spindles and mandrels, non-reciprocating bearings for supporting the ends of the mandrels, and manually controllable means for moving the spindles and mandrels abnormally to withdraw the mandrels from the 35 bearings to permit the unloading and loading of the mandrels.

6. The combination in a milling machine 40 of a spindle, a blank-holding mandrel carried by the spindle, a rotatable milling cutter adapted to engage a blank on the mandrel, a non-reciprocating bearing for supporting one end of the mandrel, a drum 45 rotatable about an axis parallel to the spindle and having a cam groove, and a roller connected with the spindle and extending into the groove whereby the spindle is reciprocated as the drum is turned, the drum 50 also having a supplemental longitudinal groove permitting an abnormal backward movement of the spindle to withdraw the mandrel from the non-reciprocating bearing.

55 7. The combination in a milling machine of a spindle, a blank-holding mandrel carried by the spindle, a rotatable milling cutter adapted to engage a blank on the mandrel, a non-reciprocating bearing for supporting the end of the mandrel, a drum 60 rotatable about an axis parallel to the spindle and having a cam groove, a roller connected with the spindle and extending into the groove whereby the spindle is reciprocated 65 as the drum is turned, the drum also having

a supplemental longitudinal groove permitting an abnormal backward movement of the spindle to withdraw the mandrel from the non-reciprocating bearing, an element carried by the spindle and having a spiral 70 cam groove, and a roller projecting into the groove and fixed against longitudinal movement whereby the spindle is turned during longitudinal movement, the said element having a longitudinal groove connected with 75 the cam groove whereby the aforesaid abnormal backward movement of the spindle is permitted.

8. The combination in a milling machine of a plurality of parallel blank-carrying 80 spindles, a plurality of milling cutters rotatable about parallel axes and adapted respectively to engage blanks carried by the spindles, means for relatively reciprocating the spindles in unison longitudinally to effect 85 milling, and automatically acting means for separating the spindles and cutters during movement in one direction and for restoring them to normal relationships during movement in the other direction. 90

9. The combination in a milling machine of a plurality of parallel blank-carrying spindles, a plurality of milling cutters rotatable about parallel axes and adapted respectively to engage blanks carried by the 95 spindles, means for relatively reciprocating the spindles in unison longitudinally to effect milling, means for turning the spindles in synchronism during milling to effect the cutting of spiral grooves in the blanks, and automatically acting means for separating the spindles and cutters during movement in one direction and for restoring them to 100 normal relationships during movement in the other direction. 105

10. The combination in a milling machine of a reciprocating table, an apron plate pivoted to the table for movement about an axis parallel to the lines of reciprocation, a rotatable spindle carried by the apron 110 plate parallel to the axis of the pivot thereof, a rotatable milling cutter adapted to engage a blank carried by the spindle, and means for holding the apron plate in a normal upper position with the blank engaged 115 by the cutter during movement of the table in one direction and for moving it about its pivot to a lower retracted position during movement of the table in the other direction. 120

11. The combination in a milling machine of a reciprocating table, an apron plate connected to the table for movement upward and downward, a rotatable spindle carried by the apron plate parallel to the 125 lines of reciprocation of the table, a rotatable milling cutter adapted to engage a blank carried by the spindle, and a pair of toggle links for holding the apron plate in a normal upper position with the blank en- 130

- gaged by the cutter during movement of the table in one direction and for moving it to a lower retracted position during movement of the table in the other direction.
- 5 12. The combination in a milling machine of a reciprocating table, an apron plate connected to the table for movement upward and downward, a rotatable spindle carried by the apron plate parallel to the lines of reciprocation of the table, a rotatable milling cutter adapted to engage a blank carried by the spindle, a pair of toggle links for holding the apron plate in a normal upper position with the blank engaged by the cutter during movement of the table in one direction and for moving it to a lower retracted position during movement of the table in the other direction, a roller carried by the toggle links at the joint between them, and a cam member engaging the roller to operate the links.
- 10 13. The combination in a milling machine of a reciprocating table, an apron plate connected to the table for movement upward and downward, a rotatable spindle carried by the apron plate parallel to the lines of reciprocation of the table, a rotatable milling cutter adapted to engage a blank carried by the spindle, a stop for limiting upward movement of the apron plate, and toggle links for holding the apron plate in a normal upper position in engagement with the stop during movement of the table in one direction and for moving it to a lower retracted position during movement of the table in the other direction.
- 15 14. The combination in a milling machine of a reciprocating table, an apron plate connected to the table for movement upward and downward, a rotatable spindle carried by the apron plate parallel to the lines of reciprocation of the table, a rotatable milling cutter adapted to engage a blank carried by the spindle, a stop for limiting upward movement of the apron plate, and toggle links for holding the apron plate in a normal upper position in engagement with the stop during movement of the table in one direction and for moving it to a lower retracted position during movement of the table in the other direction, and means for adjusting one of the pivots for the links.
- 20 15. The combination in a milling machine of a plurality of parallel blank-carrying spindles, a plurality of milling cutters rotatable about parallel axes and adapted respectively to engage blanks carried by the spindles, means for relatively reciprocating the spindles in unison longitudinally to effect milling, and means for turning the spindles in synchronism optionally in either direction during milling to effect the cutting of right or left spiral grooves in the blanks.
- 25 16. The combination in a milling machine of a plurality of parallel blank-carrying

spindles, a plurality of milling cutters rotatable about parallel axes and adapted respectively to engage blanks carried by the spindles, means for relatively reciprocating the spindles in unison longitudinally to effect 70 milling, means for turning the spindles in synchronism optionally in either direction during milling to effect the cutting of right or left spiral grooves in the blanks, and means for relatively adjusting the spindles 75 and the cutters angularly to conform to the pitch angle of the spirals.

17. The combination in a milling machine of a plurality of parallel blank-carrying spindles, a plurality of rotatable milling cutters adapted respectively to engage blanks carried by the spindles and having their cutting planes coincident and at an angle to the plane of the spindle axes, means whereby the spindles may be adjusted angularly, 80 means for relatively moving the spindles in unison longitudinally and for simultaneously turning them to effect the milling of spiral grooves in the blanks, and means for changing the turning movement of the spindles whereby the pitch angle of the spirals 90 may be the same as the angle of the cutting planes of the cutters.

18. The combination in a milling machine of a blank-carrying spindle, a rotatable milling cutter adapted to engage a blank carried by the spindle, means for relatively moving the spindle longitudinally, an element carried by one of the spindles having two oppositely formed spiral cam grooves, and a 95 roller adapted to project into either of the grooves and fixed against longitudinal movement whereby the spindle may be turned in either direction during longitudinal movement.

19. The combination in a milling machine of a plurality of parallel blank-carrying spindles, a plurality of milling cutters rotatable about parallel axes and adapted respectively to engage blanks carried by the spindles, means for relatively moving the spindles in unison longitudinally, means for connecting the spindles for simultaneous rotative movement, an element carried by one of the spindles having two oppositely 110 formed spiral cam grooves, and a roller adapted to project into either of the grooves and fixed against longitudinal movement whereby the spindles may be turned in either direction during longitudinal movement.

120 20. In a milling machine, the combination of a main frame, a plurality of rotatable cutters carried by the main frame and arranged with their axes horizontal and in the same vertical plane, a supplemental frame vertically pivoted to the main frame and adapted to be secured in either of two positions, a plurality of spindles carried by the supplemental frame and arranged with their axes horizontal and in the same vertical plane, 125 130

and means bodily movable with the supplemental frame and adapted to longitudinally reciprocate the spindles whereby blanks carried thereby are brought respectively into 5 engagement with the cutters.

21. In a milling machine, the combination of a main frame, a plurality of rotatable cutters carried by the main frame and arranged with their axes horizontal and in the same 10 vertical plane, a supplemental frame vertically pivoted to the main frame and adapted to be secured in either of two positions, a plurality of spindles carried by the supplemental frame and arranged with their axes 15 horizontal and in the same vertical plane, a rotatable shaft bodily movable with the supplemental frame, a cam on the shaft adapted to longitudinally reciprocate the spindles whereby blanks carried thereby are brought 20 respectively into engagement with the cutters, and a second cam on the shaft adapted to hold the spindles in normal position during movement in one direction and to lower them during movement in the other direc- 25 tion.

22. The combination in a milling machine of a plurality of parallel blank-carrying spindles, a plurality of milling cutters rotatable about parallel axes and having their 30 cutting planes coincident, the said cutters being adapted respectively to engage blanks carried by the spindles, means for relatively moving the spindles in unison longitudinally to effect milling, and means for indexing 35 the spindles simultaneously through equal angles.

23. The combination in a milling machine of a plurality of parallel blank-carrying spindles, a plurality of milling cutters rotatable about parallel axes and adapted respectively to engage blanks carried by the spindles, means for relatively reciprocating the spindles in unison longitudinally to effect milling, and means for automatically 40 indexing the spindles simultaneously through equal angles after each milling operation.

24. The combination in a milling machine of a plurality of parallel blank-carrying spindles, a plurality of milling cutters rotatable about parallel axes and adapted respectively to engage blanks carried by the spindles, means for relatively reciprocating the spindles in unison longitudinally to effect milling, means for automatically indexing the spindles simultaneously through equal angles after each milling operation, and means for automatically stopping the machine after the spindles have been indexed through a complete revolution. 50

25. The combination in a milling machine of a parallel blank-carrying spindle, a rotatable milling cutter adapted to engage a blank carried by the spindle, means for relatively reciprocating the spindle longitudinally to effect milling, means for turning the spindle 55

65 respectively reciprocating the spindle longitudinally to effect milling, means for turning the spindle optionally in either direction during milling to effect the cutting of right or left spiral grooves in the blank, and means for indexing the spindle optionally in either 70 direction simultaneously through equal angles.

26. The combination in a milling machine of a plurality of parallel blank-carrying spindles, a plurality of milling cutters rotatable about parallel axes and adapted respectively to engage blanks carried by the spindles, means for relatively reciprocating the spindles in unison longitudinally to effect milling, means for turning the spindles 75 in synchronism optionally in either direction during milling to effect the cutting of right or left spiral grooves in the blanks, and means for indexing the spindles optionally in either direction simultaneously 80 through equal angles.

27. The combination in a milling machine of a blank-carrying spindle, a rotatable milling cutter adapted to engage a blank carried by the spindle, means for relatively reciprocating the spindle longitudinally to effect milling, means for turning the spindle 90 optionally in either direction during milling to effect the cutting of right or left spiral grooves in the blank, means for indexing the spindle optionally in either direction simultaneously 95 through equal angles, and means for stopping the machine after the spindle has been indexed through a complete revolution. 100

28. In a milling machine, the combination of a rotatable spindle, a rotatable milling cutter adapted to engage a blank carried by the spindle, means for longitudinally reciprocating the spindle, a sleeve mounted concentrically with the spindle and movable longitudinally therewith, means dependent upon longitudinal movement of the sleeve for rotating it, means normally connecting the sleeve and spindle for synchronous rotative movement, and means for momentarily disconnecting the sleeve and spindle during each reciprocation to thereby effect indexing of the spindle. 105

29. In a milling machine, the combination of a rotatable spindle, a rotatable milling cutter adapted to engage a blank carried by the spindle, means for longitudinally reciprocating the spindle, a sleeve mounted concentrically with the spindle and movable longitudinally therewith, means dependent upon longitudinal movement of the sleeve for rotating it, means normally connecting the sleeve and spindle for synchronous rotative movement, means for momentarily disconnecting the sleeve and spindle during each reciprocation, and means for stopping the rotative movement of the spindle when 115 120 125

it is disconnected from the sleeve, whereby relative movement of the sleeve takes place to effect indexing.

30. In a milling machine, the combination 5 of a rotatable spindle, a rotatable milling cutter adapted to engage a blank carried by the spindle, means for longitudinally reciprocating the spindle, a sleeve mounted concentrically with the spindle and movable longitudinally therewith, means dependent 10 upon longitudinal movement of the sleeve for rotating it, a movable tooth normally connecting the sleeve and spindle for synchronous rotative movement, and a cam element 15 for momentarily moving the tooth to disconnect the sleeve and spindle at a definite position during each reciprocation to thereby effect indexing of the spindle.

31. In a milling machine, the combination 20 of a rotatable spindle, a rotatable milling cutter adapted to engage a blank carried by the spindle, means for longitudinally reciprocating the spindle, a sleeve mounted concentrically with the spindle and movable longitudinally therewith, means dependent 25 upon longitudinal movement of the sleeve for rotating it, means normally connecting the sleeve and spindle for synchronous rotative movement, means for momentarily disconnecting 30 the sleeve and spindle at a definite position during each reciprocation of the spindle, an arm connected with the spindle, and a stop adapted to engage the arm to stop the rotation of the spindle when 35 the sleeve and spindle are disconnected, whereby relative movement of the sleeve takes place to effect indexing.

32. In a milling machine, the combination 40 of a rotatable spindle, a rotatable milling cutter adapted to engage a blank carried by the spindle, means for longitudinally reciprocating the spindle, a sleeve mounted concentrically with the spindle and movable longitudinally therewith, means dependent 45 upon the longitudinal movement of the sleeve for rotating it, means normally connecting the sleeve and spindle for synchronous rotative movement, means for momentarily disconnecting the sleeve and 50 spindle near the end of each backward movement of the spindle, a ratchet wheel connected with the spindle, an arm rotatable about the spindle axis and having a spring-pressed pawl engaging the ratchet wheel, a 55 stop adapted to engage the arm near the end of the forward movement of the spindle to cause it to carry the pawl relatively backward over the teeth of the ratchet, and a second stop adapted to engage the arm near 60 the end of the backward movement of the spindle to stop the rotation of the spindle when the sleeve and spindle are disconnected, whereby relative movement of the sleeve takes place to effect indexing.

33. In a milling machine, the combination 65 of a rotatable spindle, a rotatable milling cutter adapted to engage a blank carried by the spindle, means for longitudinally reciprocating the spindle, a sleeve mounted concentrically with the spindle and movable longitudinally therewith, means dependent 70 upon longitudinal movement of the sleeve for rotating it, means normally connecting the sleeve and spindle for synchronous rotative movement, means for momentarily disconnecting the sleeve and spindle at a definite position during each reciprocation of the spindle to effect indexing, an arm connected with the spindle independently 75 of the sleeve, and means adapted to be engaged by the arm to stop the operation of the machine when the spindle has been indexed through a complete revolution.

34. In a milling machine, the combination 80 of a rotatable spindle, a rotatable milling cutter adapted to engage a blank carried by the spindle, means for longitudinally reciprocating the spindle, a sleeve mounted concentrically with the spindle and movable longitudinally therewith, means dependent 85 upon longitudinal movement of the sleeve for rotating it optionally in either direction, means normally connecting the sleeve and spindle for synchronous rotative movement, and means operable for either direction of 90 spindle rotation for momentarily disconnecting the sleeve and spindle at a definite position during each reciprocation to thereby effect indexing of the spindle.

35. In a milling machine, the combination 100 of a rotatable spindle, a rotatable milling cutter adapted to engage a blank carried by the spindle, means for longitudinally reciprocating the spindle, a sleeve mounted concentrically with the spindle and movable longitudinally therewith, means dependent 105 upon longitudinal movement of the sleeve for rotating it optionally in either direction, means normally connecting the sleeve and spindle for synchronous rotative movement, means operable for either direction of 110 spindle rotation for momentarily disconnecting the sleeve and spindle at a definite position during each reciprocation to thereby effect indexing of the spindle, and means for stopping the rotative movement of the spindle when it is disconnected from the sleeve, whereby relative movement of the sleeve takes place to effect 115 indexing.

36. In a milling machine, the combination 120 of a rotatable spindle, a rotatable milling cutter adapted to engage a blank carried by the spindle, means for longitudinally reciprocating the spindle, a sleeve mounted concentrically with the spindle and movable longitudinally therewith, means dependent 125 upon longitudinal movement of the sleeve

- for rotating it optionally in either direction, a movable tooth normally connecting the sleeve and spindle for synchronous rotative movement, and two cam elements for 5 momentarily moving the tooth to disconnect the sleeve and spindle at a definite position during each reciprocation of the spindle to thereby effect indexing of the spindle, one cam element being operable for one direction 10 of rotation and the other for the other direction.
37. In a milling machine, the combination of a rotatable spindle, a rotatable milling cutter adapted to engage a blank carried by 15 the spindle, means for longitudinally reciprocating the spindle, a sleeve mounted concentrically with the spindle and movable longitudinally therewith, means dependent upon longitudinal movement of the sleeve 20 for rotating it optionally in either direction, means normally connecting the sleeve and spindle for synchronous rotative movement, means operable for either direction of rotation for momentarily disconnecting the 25 sleeve and spindle at a definite position during each reciprocation of the spindle, an arm connected with the spindle, and two stops adapted to engage the arm to stop the rotation of the spindle when the sleeve and 30 spindle are disconnected, whereby relative movement of the sleeve takes place to effect indexing, one stop being operable for one direction of rotation and the other for the other direction.
38. In a milling machine, the combination of a rotatable spindle, a rotatable milling cutter adapted to engage a blank carried by the spindle, means for longitudinally reciprocating the spindle, a sleeve mounted 40 concentrically with the spindle and movable longitudinally therewith, means dependent upon longitudinal movement of the sleeve for rotating it optionally in either direction, means normally connecting the sleeve and 45 spindle for synchronous rotative movement,

means for momentarily disconnecting the sleeve and spindle near the end of each backward movement of the spindle, a ratchet wheel connected with the spindle, an arm rotatable about the spindle axis and having a 50 spring-pressed pawl engaging the ratchet wheel, the ratchet wheel and arm being reversible on the spindle in accordance with the direction of rotation, two stops adapted respectively to engage the arm near the end 55 of the forward movement of the spindle to cause it to carry the pawl relatively backward over the teeth of the ratchet and to engage the arm near the end of the backward movement of the spindle to stop the rotation 60 of the spindle when the sleeve and spindle are disconnected, whereby relative movement of the sleeve takes place to effect indexing, the functions of the said stops being interchanged when the direction of rotation is 65 reversed.

39. In a milling machine, the combination of a rotatable spindle, a rotatable milling cutter adapted to engage a blank carried by 70 the spindle, means for longitudinally reciprocating the spindle, a sleeve mounted concentrically with the spindle and movable longitudinally therewith, means dependent upon longitudinal movement of the sleeve for rotating it optionally in either direction, 75 means normally connecting the sleeve and spindle for synchronous rotative movement, means operable for either direction of spindle rotation for momentarily disconnecting the sleeve and spindle at a definite 80 position during each reciprocation of the spindle to effect indexing, an arm connected with the spindle independently of the sleeve, and means adapted to be engaged by the arm to stop the operation of the machine 85 when the spindle has been indexed through a complete revolution in either direction.

In testimony whereof, I hereto affix my signature.

FRIEDERICH MÜLLER.
